C. L. BASTIAN.
FLUID PRESSURE REGULATING VALVE.
APPLICATION FILED JAN. 22, 1919.

1,394,395.

Patented Oct. 18, 1921.

UNITED STATES PATENT OFFICE.

CHARLES L. BASTIAN, OF CHICAGO, ILLINOIS.

FLUID-PRESSURE-REGULATING VALVE.

1,394,395.

Specification of Letters Patent. Patented Oct. 18, 1921.

Application filed January 22, 1919. Serial No. 272,421.

To all whom it may concern:

Be it known that I, CHARLES L. BASTIAN, a citizen of the United States, residing at Chicago, in the county of Cook and State 5 of Illinois, have invented certain new and useful Improvements in Fluid - Pressure - Regulating Valves, of which the following is a specification.

This invention relates to fluid pressure 10 regulating valves of the type shown in my Patents No. 1,161,917 patented November 30, 1915 and No. 1,217,901 patented March 6, 1917.

I have found from practical experience 15 that the valve disks are often excessively worn and permanently injured by carelessness in adjusting the spring tension to the desired pressure and sometimes it happens that the full pressure is allowed to act 20 against the diaphragm with the spring tension released. In such cases the disk is often forced by the pressure against the nozzle seat until it is deeply cut and oftentimes cracked or broken, thereby rendering it in- 25 effective for further use. It is inexpedient to broaden the nozzle seat to prevent such injury to the disk because as the engaging surface is increased the sensitiveness of operation is decreased and much loss of pressure 30 results.

It is the object of my invention, therefore, to protect the valve disk against excessive wear and injury and at the same time maintain the desired sensitiveness of operation.

I have also found that when one spring is 35 used within another spring to provide the tension adjustment for the diaphragm there is a possibility, under some of the many conditions affecting the use of these valves, that 40 the springs may be dislodged from their proper position in the bonnet and in relation to each other in a manner which will prevent their proper operation.

It is also the object of my invention, there- 45 fore, to provide means for maintaining the springs in correct position in the bonnet of the valve so as to insure their proper operation at all times.

In the accompanying drawings illustrating one embodiment of the invention—

Figure 1 is a central sectional view of the regulating valve;

Fig. 2 is a plan view, partly in section, looking down upon the springs and dia- 5 phragm with the bonnet removed;

Fig. 3 is an enlarged sectional view of the nozzle;

Fig. 4 is a bottom plan view of the nozzle, as shown in Fig. 3;

Fig. 5 is a detail sectional view on a larger 60 scale to show the double seat on the nozzle;

Fig. 6 is a perspective view of the dia- phragm plate;

Fig. 7 is a detail view of the disk retainer.

Referring to the drawings, 8 is the body 65 portion of the casing provided with two outlets 9, one for a pressure gage and the other for delivery to the work. The gas enters the valve through a pipe 10 rigid with the body and provided with a nozzle 70 11 located within the yoke 12. This yoke is connected with the diaphragm 13 and carries the disk 14 to and from the seat formed on the discharge end of the nozzle.

The disk is made of fiber, hard rubber or 75 other suitable material and is snugly fitted, preferably under pressure, in the recess 15 against the annular shoulder 16 formed by the inclined walls 17 of the retainer ring 18 which threadedly engages the disk support 80 19. The retainer carrying the disk is screwed into place in the disk support until the disk is rigidly seated in the recess 19' of said support, whereupon the disk will be securely confined within the support by the retainer 85 and the retainer not only serves to hold the disk in place by engagement with the outer face thereof but it also confines the disk by engaging the periphery thereof and thereby tends to prevent the disk from spreading 90 or breaking.

The nozzle 11 is provided with an external stepped series of annular valve seats, the illustration in the drawing being that of two seats, 20, 21, arranged in different planes 95 one above the other, the lower primary seat 20 being located adjacent the nozzle opening and the upper or secondary seat 21 being disposed around the primary seat 20. I prefer to make the primary seat with a narrower 100 engaging surface than the secondary seat, as shown in Fig. 5, but the primary seat should have sufficient engaging surface to form an effective seal while still preserving the desired sensitiveness of operation under 105 the normal and proper conditions of operation of the valve.

A screw 22 operates in the bonnet 23 which is threadedly engaged with the body of the casing and incloses the outer heavy 110

spring 24 and the inner lighter spring 25. The low pressures are obtained by the inner weaker spring and the heavy pressures by the outer stronger spring in conjunction with the inner spring. A cap 26 is engaged by the screw and acts as a follower to compress first the inner spring and then the outer spring, as will be readily understood. The inner spring is engaged at its ends with 10 and guided by a projection 27 on the cap 26 and a projection 28 on the diaphragm plate 29 which is secured to the yoke 12 in the usual manner. The outer spring fits freely within the bonnet and upon the inner spring 15 and it is held in proper position by the guides 30 on the diaphragm plate. Thus the inner spring is interiorly guided and the outer spring is exteriorly guided and it is not necessary to fit the outer spring on 20 the inner spring so closely that the convolutions of the springs will catch upon each other or so loosely that the inner end of the outer spring may drop out of centered position and thus cause imperfect operation of 25 the diaphragm. The interior guiding of the inner spring holds that spring in centered position in the bonnet and upon the diaphragm and the exterior guiding of the outer spring maintains the same in proper 30 relation to the inner spring, as well as to the diaphragm, so that there will be no interference of one spring with the other in actual use and both springs will always be maintained in proper relation to each other 35 and to the diaphragm.

In practice the diaphragm is adjusted by properly tensioning the springs to provide for an even flow of gas at a predetermined pressure. The valve disk is carried to and 40 from its seat against the nozzle by the diaphragm as the pressure within the casing of the valve fluctuates. Thus, when the pressure is slightly in excess of the spring tension the disk will be seated; and when the 45 pressure is decreased slightly below the tension of the springs the disk will be unseated. During the normal operation of the valve under a proper adjustment of the springs the disk will be seated against the 50 inner, lower primary seat 20. This seat is annular in form and by reason of the narrowness of its engaging surface a very sensitive operation of the valve is obtained. In event that the springs are insufficiently tensioned to provide a proper balance for the 55 valve disk, or in the event that the springs are entirely released, it may happen that the pressure will be sufficient to force the disk not only against the primary seat 20 but also 60 against the secondary seat 21, and in such case the combined areas of the two seats will be amply sufficient to provide an effective seal. Thus the primary seat with a comparatively narrow annular engaging surface 65 is sufficient under normal and proper ad-

justments and operation of the valve to seal the nozzle and maintain the desired sensitivity of operation, while the secondary seat constitutes a safety and provides that additional engaging surface which may be 70 necessary to seal the nozzle under abnormal conditions of operation. This secondary seat is brought into action automatically to supplement the primary seat when it becomes necessary in order to seal the nozzle against 75 the pressure which brings this secondary seat into action. And I have found that this arrangement of a primary and a secondary seat not only secures superior sealing effect as herein described but also protects 80 the seat against excessive wear and injury. If the primary seat alone proves to be insufficient under any conditions to provide an effective seal for the nozzle the secondary seat will automatically be brought into sealing action before the disk is damaged and the combined seats are sufficient to provide an effective seal for the nozzle under all conditions and are of such area that the seal will be provided without damage to the disk. 85 90

I am aware that my present invention may be embodied in different ways in valves of different kinds and that changes in the form and proportion and arrangement of parts may be made without departing from the 95 spirit or sacrificing the advantages of the invention and I therefore reserve the right to make all such adaptations and changes as may fairly fall within the scope of the accompanying claims. 100

I claim:

1. In a pressure regulating valve, the combination of an inlet nozzle, a support having a recess therein, a disk arranged in said recess in operative position to seal the nozzle, and a retainer engaging said disk peripherally and on the outer face thereof and threadedly engaging said recess to secure the disk in said support. 105

2. In a pressure regulating valve, the combination of an inlet nozzle, an exteriorly threaded retainer ring having an annular shoulder therein, a disk securely held in said ring against said shoulder, and a support having a recess therein to receive said disk 115 and threaded to receive said ring.

3. In a pressure regulating valve, the combination of an inlet nozzle, an exteriorly threaded retainer ring having an annular shoulder therein, a disk forced into said ring against said shoulder under pressure, whereby said ring tightly confines peripherally a substantial portion of said disk, and means for supporting said disk with the ring thereon and the face of that portion of the disk 125 confined within the ring in operative relation to said inlet nozzle.

4. A pressure-regulating-valve nozzle having two independent seats in different planes.

5. A pressure-regulating-valve nozzle hav- 130

- ing a stepped series of annular valve seats at the discharge end of the nozzle to successively come into engagement with a valve.
6. A pressure-regulating-valve nozzle having an external stepped series of annular valve seats surrounding the discharge end of the nozzle and adapted to successively come into engagement with a valve.
7. A pressure-regulating-valve nozzle having two independent annular seats arranged one within the other in different planes and with engaging surfaces of different widths.
8. A pressure-regulating-valve nozzle having an external stepped series of annular valve seats of different widths and surrounding the discharge end of the nozzle.
9. In a pressure-regulating-valve, the combination of a nozzle and a diaphragm-controlled valve for the nozzle, said valve having a flat face to seat against the delivery end of the nozzle, and said nozzle having an external stepped series of annular valve seats to successively come into engagement with the flat face of the valve as the latter wears.
10. As a new article of manufacture, a pressure-regulating-valve nozzle comprising a body provided with a longitudinal open-ended passage, said body having an intermediate external enlargement constituting a wrench seat, the inlet end of the nozzle being cylindrical and externally screw threaded, the discharge end of the nozzle having an external annular valve seat surrounding the longitudinal passage, and also provided with another external annular valve seat surrounding the longitudinal passage and in rear of the first mentioned seat, the two seats constituting a stepped series of seats.
11. In a pressure regulating valve, a nozzle of hard material adapted to be closed by a valve disk of relatively soft material, said nozzle having a stepped series of valve seats adapted to successively come into contact with said valve disk as said nozzle penetrates said disk due to wear or pressure.
12. In a pressure regulating valve, a nozzle of hard material adapted to be closed by a valve disk of relatively soft material, said nozzle having two independent annular seats in stepped relation and of different widths adapted to successively engage the said valve disk as said nozzle penetrates said disk due to wear or pressure.
13. In a pressure regulating valve, a nozzle of hard material adapted to be closed by a soft valve disk, said nozzle having two independent annular seats arranged in stepped relation, the foremost seat being narrow, the rearmost seat being broad and engaging the said valve disk after the foremost seat has penetrated said valve disk.
14. In a pressure regulating valve, a hard nozzle adapted to be closed by a soft disk, said nozzle having a narrow seat at its end to form a sensitive seal with said disk and in stepped relation thereto, a broad seat adapted to contact with said disk when said narrow seat has penetrated said disk due to wear or pressure.

CHARLES L. BASTIAN.
